UNITED STATES PATENT OFFICE.

THOMAS A. KEEFER, OF DAYTON, OHIO, ASSIGNOR TO THE RECORDING DEVICES COMPANY, OF DAYTON, OHIO, A CORPORATION OF OHIO.

RECORDING-LOCK.

1,309,437.

Specification of Letters Patent.

Patented July 8, 1919.

Application filed September 17, 1917. Serial No. 191,722.

To all whom it may concern:

Be it known that I, THOMAS A. KEEFER, a citizen of the United States, residing at Dayton, in the county of Montgomery and State of Ohio, have invented certain new and useful Improvements in Recording Locks, of which the following is a specification, reference being had therein to the accompanying drawing.

10 This invention relates to recording locks, and the object of the invention is to provide a lock of this character which will be simple in its construction and certain and accurate in its operation.

15 It is also an object of the invention to provide in a device of this kind a time recording device which will be actuated from a source of stored energy which will be independent of, but will be controlled by, a 20 clock mechanism.

It is also an object of the invention to provide a bolt actuating device having movement in one direction only to move the bolt in both directions; and to provide means for 25 positively preventing all movement of the bolt independently of the bolt actuating device.

It is also an object of the invention to provide means controlled by the key against 30 removal after the bolt has been released for operation, and to release the key for removal after the bolt has been operated and the actuating mechanism returned to its normal position; and to provide means of this kind 35 which will be of a very simple character and will comprise but a few parts.

It is also an object of the invention to provide the recording mechanism with a consecutive numbering device, having means 40 by which it will be advanced one unit upon each operation of the bolt actuating mechanism.

It is also an object of the invention to provide in combination with a recording device comprising a series of alined counter wheels, a key actuated key identifying device.

It is also an object of the invention to provide an improved transfer mechanism for 50 transferring the count from one counter wheel to the other in said recording mechanism.

It is also an object of the invention to provide a separable operating member for 55 the bolt actuating mechanism.

It is also an object of the invention to provide automatic actuating means for making a record on each removal of the casing of the lock.

Further objects of the invention will appear as the mechanism is described in detail.

In the accompanying drawings Figure 1 is a vertical sectional view taken centrally through a lock embodying my invention; Fig. 2 is a front elevation of the recording and bolt actuating devices with the casing in section; Fig. 3 is a transverse section taken on the line 3—3 of Fig. 1 looking in the direction of the arrows; Fig. 4 is a detail sectional view, partially broken away, of the transfer mechanism for the recording device; Fig. 5 is a detail view, partly broken away, of the driving mechanism for the minute counter wheel; Fig. 6 is a detail view of the escutcheon showing in elevation 75 the locking device for the bolt actuating mechanism and for the key; Fig. 7 is a similar view showing the bolt actuating device released; Fig. 8 is a detail view of the escapement for controlling the movement of 80 the minute counter wheel; Fig. 9 is an elevation, partly broken away, of a portion of the casing showing the housing for the detachable operating member; Fig. 10 is a detail view of the detachable operating 85 member; and Fig. 11 is a view on an enlarged scale of a portion of a record produced by the machine.

In these drawings I have illustrated one embodiment of my invention and have shown the same as comprising a base plate 1 rigidly secured to a door 2 and adapted to carry the several parts of the bolt actuating and recording mechanisms. Removably mounted on the base plate 1 is a casing 3 which encloses the mechanism carried by the base plate and is normally secured to the base plate by means of a lock 4. A bolt 5 is mounted on the base plate for transverse sliding movement through a guide-way 6 secured to the base plate. This bolt is preferably moved into and out of its locking position by means of operating members, or knobs, arranged on opposite sides of the door, and one of which is controlled by the key. The operating members are connected with bolts through suitable actuating mechanism which is here shown as comprising a shaft 7 journaled in a bearing in the base plate 1 and extending through an elongated 110

opening 8 formed in the bolt, whereby it is enabled to support the inner end of the bolt. Preferably this shaft is rotatable in one direction only, and means are provided whereby successive movements thereof in the same direction will cause the bolt to be moved in opposite directions. To this end I have secured to the shaft 7, between the bolt and the base plate 1, a ratchet wheel 9 with 10 which engages a spring pressed pawl 10. To cause the bolt to be actuated in opposite directions upon the successive movements of the shaft in the same direction I have secured to the shaft a cam 11, which is arranged between two projections, or studs, 12, carried by the bolt, and, in the present instance, provided with rollers to reduce the friction. The cam is so shaped that a half rotation of the shaft will cause the cam to bear against one of the studs 12 and move the bolt in one direction, and the next half rotation of the shaft will cause the cam to bear against the other stud and move the bolt in the opposite direction. The shape of 25 the cam is such that the diameter of that portion of the same which lies between the two studs, in any position of the cam, is approximately equal to the distance between the studs, thus the bolt is positively locked 30 against all movement independently of the cam. To center the actuating mechanism and check its movement when the bolt has completed its movement in one direction the ratchet wheel 9 is provided with recesses 13 35 arranged in diametrically opposite portions thereof and adapted to receive a yieldable detent 14 when the actuating devices are in their home positions.

The bolt actuating shaft 7 may be of any 40 suitable construction and may be connected with the operating members, or knobs, in any suitable manner. I have formed the shaft in several pieces, the central portion 7, which carries the bolt actuating cam, being journaled in the base plate 1 and in a bearing 15 carried by a depending bracket 16. That portion of the shaft which extends through the door for connection with the outer knob, which is shown at 17, is separate 45 from the main portion 7 of the shaft and has secured thereto a clutch collar 18 coöperating with a similar collar 19 on the adjacent end of the main portion of the shaft to form an overrunning clutch connection 50 which will permit the portion 7 of the shaft to rotate relatively to the portion 17 thereof. The clutch collar 19 extends beyond the end of the shaft so as to form a socket to receive the adjacent end of the portion 17 of the shaft, whereby these parts are retained in alinement. An operating member, such as a 55 knob 20, is mounted on the outer end of the portion 17 of the shaft and, in the present instance, this knob is provided with a trunnion 21 which is journaled in an escutcheon 22 secured to the outer side of the door. A spring 23 is confined between the collar 18 on the shaft 17 and the inner end of the trunnion of the knob and serves to hold the clutch collars 18 and 19 normally in engagement. In order that the escutcheon may be readily removed the connection between the knob and the portion 17 of the shaft is a separable one. As here shown the shaft is provided with an elongated slot 24 adapted 70 to receive a pin 25 extending across the bore of the hollow trunnion. Thus when the escutcheon is removed the knob will be withdrawn from the shaft, and inasmuch as this removes all pressure from the spring 23 the 80 portion 17 of the shaft can also be removed.

It is not necessary that an operating member be provided on the inner side of the door, because it is not often that it is desired to lock the door from the inside, but 85 such an operating member when provided must obviously be independent of the key controlled mechanism, as the key, in the construction here shown, can only be manipulated from the outside of the door. If 90 an operating member is provided on the inside of the door and is always free to operate, it is liable to be actuated by unauthorized persons, either from curiosity or malice, and records made which do not 95 represent the locking or unlocking of the door. To overcome this objection and at the same time to enable the door to be locked from the inside, should this be desired, I have provided a detachable operating member. The clutch connection 18 and 19 between the two parts of the bolt actuating shaft enables the main portion 7 thereof to be operated independently of the outer portion 17 thereof, which outer portion, as will 100 hereinafter appear, is normally locked against movement. The inner end of the bolt operated shaft is also separate from the main portion 7 thereof, as shown at 26, and is rotatably and slidably mounted in a housing 27 mounted in an opening formed in the casing 3 and rigidly secured to that casing. As here shown the housing comprises inner and outer portions adapted to be placed against the respective surfaces of the casing and to be connected one to the other and to the casing by screws 28. The adjacent ends of the main portion 7 of the shaft and the portion 26 thereof are provided with tongue and groove to form a slip connection 110 115 between the same, and the other end of the portion 26 of the shaft is provided with a disk-like head 30 which is slidably and rotatably mounted in the housing 27. Confined between the disk-like head 30 of the 120 shaft and the inner end of the housing 27 is a spring 31 which tends to move the portion 26 of the shaft outward and to disconnect the same from the main portion 7 of the shaft, this outward movement being 130

limited by a flange 32 carried by the outer part of the housing. The disk-like head 30 is provided with notches 33, arranged on the opposite sides thereof and adapted to be moved into alignment with corresponding notches 34 formed in the opposite sides of the flange 32 of the housing. A suitable actuating member is provided for forcing the portion 26 of the shaft into engagement 5 with the part 7 thereof and for rotating the shaft as a whole. This operating member, or handle, which is shown at 35, in Fig. 10, is provided with a flat end portion having two inwardly extending prongs 36 adapted 10 to enter the aligned notches 33 and 34 in the housing 27 and disk 30. An inward thrust on the operating member will force the head or disk 30 and the shaft 26 inward and will bring the notches 37 formed in the opposite sides of the flat portion of the operating member into alignment with the flange 32. Rotatory movement imparted to the operating member will impart rotatory movement 15 to the portions 26 and 7 of the shaft and will cause the flanges of the housing to enter the notches 37 of the operating member and thus prevent the removal of the latter until the shaft has been moved through a half revolution, it being apparent that the pawl 20 and ratchet, 10 and 9, will prevent the reverse movement of the operating member. When the shaft has been brought to its home position at the end of a half revolution the spring 31 will force the disk 30 outward, 25 disconnecting the two parts of the shaft and ejecting the operating member. A pin 26 carried by the shaft 26 will enter notches 27 in the inner end of the housing 27, when the shaft section 26 is in its outer or normal 30 position, and prevent the rotation of the shaft independently of the operating device.

Suitable key controlled devices are provided for normally preventing the movement of the bolt into or out of its operative 35 position. The means for accomplishing this may take various forms, but it is desirable that it should be simple in construction and positive in its operation so that it will not be liable to become disarranged or to be rendered 40 inoperative and thus prevent the locking or unlocking of the door. In that form of the mechanism here shown this locking device is applied to the bolt operating shaft and is arranged within the escutcheon 22.

50 A locking member or plate 38 is secured to the bolt actuating shaft, preferably by mounting the same on a collar 39 which is rigidly secured to the trunnion for the knob 20 and to the shaft, the connection with the 55 shaft being formed, as heretofore explained, by the pin 25 extending through a slot 24 in the shaft. The locking plate is provided on diametrically opposite sides with notches 40 and is provided in advance of each notch 60 with a cam-shaped portion 41. Slidably

mounted on the escutcheon, for movement lengthwise thereof, is a controlling member or plate 42 which is here shown as substantially rectangular in shape and as having elongated slots 43 through which extend 70 screws 44 which serve to connect the plate to the escutcheon. The controlling member is provided at its upper end with a projection 45 adapted to enter one of the notches 40 in the locking plate when the latter is in its 75 normal or home position. A spring 46 connected at one end with the controlling plate 42 and at the other end with a pin 47 secured to the escutcheon and extending through an opening 48 in the controlling 80 plate tends to move the controlling plate upward and to hold the same in the adjacent notch 40 in the locking plate, when the latter is in its home position, or to cause it to bear against the edge of that plate 85 when the latter has been moved out of its home position. The controlling member or plate is provided in its lower portion with an irregular opening 49 through which extends the key barrel 50 of a cylinder lock, 90 which may be of any suitable or well known construction, and which is mounted in the wall of the escutcheon. Rigidly secured to the key barrel and arranged within the opening in the controlling member 42 is an actuating member, or disk, 51, having a cam-like projection, or nose, 52, arranged to coöperate with the lower edge of the opening 49 in the controlling member to impart lengthwise movement to the latter when the key 100 barrel is rotated. A spring 53 serves to hold the key barrel normally in its home position and when it is in this position the outer surface of the cam-like projection 52 of the disk 51 will lie substantially parallel with 105 the lower edge of the opening in the controlling member, and when the key has been actuated to rotate the barrel 50 the projection 52 will exert a downward thrust upon the controlling member and move the same 110 downward a distance sufficient to carry the projection 45 out of the notch 40 in the plate on the bolt actuating shaft. The lower edge of the opening 49 is provided with an offset portion to form a shoulder 54, past which 115 the projection 52 is moved by the key. As soon as the projection has cleared the shoulder the spring 46 will move the plate upward and cause the shoulder to engage the forward edge of the nose and prevent the 120 return of the disk and the key barrel to its normal position. The further rotation of the barrel is limited by a second projection, or nose, 55, arranged to engage a shoulder 56 at the upper edge of the opening 49, and inasmuch as the key can be removed from a lock of this kind only when the key barrel is in its normal position the key will be effectually locked in its barrel. The upward 125 movement of the controlling member neces- 130

sary to lock the key barrel against return movement is not sufficient to cause the projection 45 at the upper end thereof to enter the notch in the locking plate 38, but this plate is left free to rotate in a forward direction only. The rotation of the knob 20 in a direction to actuate the bolt turns the locking plate in the direction of the arrows in Figs. 6 and 7, and as the shaft approaches the end of a half-revolution the cam-shaped portion of the locking plate arranged in advance of the succeeding notch 40 engages the end of the projection 45, moves the controlling plate downward a distance sufficient to release the projection 52 of the disk 50 on the key barrel and permits the latter to be returned to its normal position by the spring 53, thus releasing the key so that it can be removed and also releasing the controlling member 52 and permitting it to move upward into the notch in the locking plate, thereby again locking the bolt actuating shaft against movement.

The recording devices may be adapted to print data of various kinds, and the present lock is designed to print the data which is desirable in a large proportion of cases. As here shown the recording device comprises instrumentalities for printing on the record and identifying mark, such as a letter or initial, to indicate which key was used to manipulate the lock, the time, the day and month on which the record was made, a consecutive number for each record printed, and a store or lock number to indicate the place at which the record was made. The time and date printing devices and the consecutive number printing devices are shown in the form of counter wheels, mounted for rotation about a common axis so as to print their data in a straight line extending transversely of the record strip, as shown in Fig. 11. The key identifying device is so arranged that the part thereof from which the record is to be printed will be moved into printing alignment with the counter wheels. The store or lock number is preferably a fixed form and is also arranged in printing alignment with the counter wheels. In the present embodiment of the invention the recording devices are carried by a supplemental frame comprising end members 57 and 58, in which is mounted a shaft about which rotate the several counter wheels. In the present drawings this shaft is shown as an enlarged tube, or cylinder, 59, to enable it to perform certain functions which will be hereinafter described. The time and date printing instrumentalities are arranged at the outer portion of the shaft 59 and as here shown comprise a minute counter wheel 60, an hour counter wheel 61, a day counter wheel 62, and a month counter wheel 63, all loosely mounted for rotation about the shaft 59.

65 The minute, hour, and day counter wheels

are controlled by a clock mechanism so that they will record time. Preferably, however, they are operated not from the clock mechanism itself, but from a source of stored energy, such as a spring, and their movements are controlled by the clock mechanism, thus imposing a very small load on the clock and avoiding any interference with the accuracy of its operation. In the present mechanism the source of stored energy constitutes a spring 64 coiled about a stud 65 mounted on the frame member 58 in axial alignment with the shaft 59. The inner end of the spring is secured to the shaft, which is held against movement, while the outer end of the spring is secured to the peripheral flange of a casing 66 which is rotatably mounted on the shaft 65 and incloses the spring. This casing is connected through suitable driving mechanism with the minute counter wheel 60, and as here shown there is rotatably mounted on the shaft 65 adjacent to the inner side of the casing a plate or collar 67 having fingers 68 extending through notches in the inner edge of the casing 66 so that the arms and the plate 67 are rigidly secured to the casing. Carried by one or both of the arms 68 is a pawl, or pawls, 69, which engage with a ratchet wheel 70 rigidly secured to a gear 71 which is rotatably mounted on the shaft 65. Thus the casing can be rotated against the tension of the spring independently of the gear 71 to wind the spring, but is held against movement in the opposite direction, due to the unwinding action of the spring, independently of the gear. Meshing with the gear 71 is a pinion 72 carried by a shaft 73 journaled in the frame member 58 and having secured to its opposite end, on the inner side of the frame member, a gear 74, which in turn meshes with a pinion 75 mounted on a stud 76 and rigidly secured to a gear 77, which meshes with a gear 78 rotatably mounted about the axis of the shaft 59 and preferably carried by a collar 79 which is connected with the end of the shaft 65 by means of a screw 80 and serves to retain said shaft in its bearing. The gear 78 is rigidly secured to the minute counter wheel 60 so that any movement of the driving gear 71 due to the expansion of the spring 64 will be transmitted to the minute counter wheel. In order to so regulate the movement imparted to the minute wheel by the spring 64 that this movement will accurately record time it is necessary that this movement be clock controlled, and to accomplish this I have rigidly secured to the gear 78 an escapement ratchet 81, see Fig. 8, which is preferably arranged between the gear and the counter wheel. Coöperating with this escapement ratchet is a double escapement pawl 82 rigidly secured to a shaft 83 journaled in the frame members 57 and 58.

and having rigidly secured thereto a rock-arm 84 having a nose 85 adapted to coöperate with a toothed wheel 86 rotatably mounted on a stud 87 carried by the base plate 1. This rotatable toothed member is connected with the clock mechanism, which is shown at 88, the connection preferably being made detachable, as by a slip connection, as shown at 89, to permit the clock to be readily removed. The rotatable member 86 is divided circumferentially into an equal number of parts, preferably 12, and in the present construction six of these parts are represented by the ends of the teeth, while the other six parts are represented by the spaces between the teeth, the width of the spaces at the circumference of the member 86 being equal to the circumferential length of the teeth. The arm 84 is acted upon by a spring 90 which holds the nose 85 against the rotatable member, or wheel, 86, and as the toothed member rotates the nose 85 will successively enter the recesses and ride over the teeth, thus imparting a rocking movement to the shaft 83 and the escapement pawl 82, the arrangement being such that this pawl will be moved in one direction each time the nose 85 enters a recess and will be rocked in the opposite direction each time the nose rides over a tooth. Each movement of the escapement pawl in either direction releases the escapement ratchet and permits it to advance one space under the expanding action of the spring, and this movement is transmitted to the minute counter wheel. In the present construction the minutes are registered in units of five and the arrangement of the teeth on the ratchet 81 is such that each movement of the ratchet will advance the minute counter wheel one space, or one unit, thus adding five-minutes to its count. The rotatable toothed member 86 being divided into twelve parts and each part being adapted to cause a reversal of the position of the escapement pawl it will be obvious that the minute wheel will be advanced twelve spaces, or sixty minutes, on each complete rotation of the rotatable member, and this member is preferably connected with the hour shaft of the clock so that each complete rotation thereof will represent one hour of time.

While I have, in the present embodiment of the invention, connected the escapement with the hour shaft of the clock and provided for the registration of minutes in units of five, it will be obvious that the minutes may be registered in units of any suitable size, and that the connection with the clock may be of any suitable kind which will properly control registration of the units of minutes. Suitable transfer mechanism is provided for transferring the count from the minutes counter wheel to the hour counter wheel and from the hour counter

wheel to the day counter wheel, this transfer mechanism being of such a character that the hour counter wheel will be advanced a space of one unit, which equals one hour, when the units counter wheel has been advanced 70 twelve units, or sixty minutes, and the day counter wheel will be advanced one unit or one day when the hour counter wheel has been advanced twenty-four units. The day counter wheel is adapted to record thirty-one days and at the end of a short month it must be manually adjusted to advance it from the last day of the short month to the first day of the next month, skipping the intervening numbers on the counter wheel. 80 It is preferable, inasmuch as this adjustment need be made but five times a year, that it should be made manually rather than that the machine should be complicated by the addition of a mechanism to automatically 85 take care of this feature of adjustment. For the same reason the months counter wheel 63 is manually adjustable. To make this adjustment it is only necessary to remove the casing from the lock so that access can be 90 had to the counter wheels and they can then be advanced.

Any suitable transfer mechanism may be utilized for transferring the count from one counter wheel to another and that shown in 95 Fig. 4 comprises a collar 91 rigidly secured to the shaft 59 and provided on diametrically opposite edges with cam-shaped portions 92. A dog 93 is pivotally mounted on the lower counter wheel, which is the minute counter 100 wheel when the transfer mechanism is interposed between the minute wheel and the hour wheel. This dog is provided with a depending portion, or lug, 94, which is held normally in engagement with the collar 91 by 105 a spring 95 and is adapted to ride over one of the cams 92 at the end of each half revolution of the minute counter wheel. The minute counter wheel, in the present construction, is provided with two series of 110 numerals, each registering from 5 to 60 minutes, to accommodate the same to the diameter of the hour wheel which carries twenty-four numerals to represent the twenty-four hours of the day, and for this 115 reason the two cams are employed. Obviously, if the transfer was to be made only upon each complete rotation of the counter wheel a single cam surface 92 would be provided. The dog is also provided with a nose 120 96 which, when the dog rides over one of the cam surfaces 92, is moved outward into a position to engage an inwardly projecting tooth 97 on the higher, or hour counter wheel, thus connecting this counter wheel 125 with the minute counter wheel and causing it to rotate therewith so long as the connection is maintained. The connection is, of course, maintained so long as the lug 94 of the dog is in engagement with the cam sur- 130

face 92 of the collar and is interrupted as soon as this lug passes the rear edge of the cam. The cam is of such a length that the connection will be maintained long enough 5 to advance the hour wheel one unit. Suitable detent and alining devices are provided for accurately positioning the counter wheels in printing alinement and for holding them against accidental displacement and, as here 10 shown, each counter wheel is provided with a series of V-shaped notches 98 and a round ended detent pawl 99 is pivotally mounted adjacent to the counter wheel and is acted upon by a spring 100 which tends to cause 15 the round head thereof to engage the V-shaped notch and properly aline the counter wheel, and to hold the same against accidental displacement without offering objectionable resistance to the movement thereof when 20 power is applied to the counter wheel to advance the same.

The consecutive numbering device comprises three axial counter wheels 101. The units counter wheel being arranged on the 25 right in Figs. 1 and 3. A suitable connection is established between the units counter wheel and the bolt actuating mechanism to cause the consecutive counter to be advanced one number each time the bolt actuating mechanism is operated and, as will hereinafter appear, the recording mechanism is actuated each time the bolt is operated, hence the records will be consecutively operated. The connection between the units 30 counter wheel and the bolt actuating mechanism is accomplished in various ways, but in the present construction I have interposed a train of gearing between the bolt actuating shaft 7 and the units counter 35 wheel. Rigidly secured to the shaft 7 is a circular disk 102 which, in the present instance, is formed integral with the ratchet wheel 9. This disk is provided with two peripheral recesses 103 arranged on diametrically opposite sides thereof and adjacent to each recess is a pin 104, the pins being in the present instance mounted in the ratchet wheel 9, which is of greater diameter than the disk 102, and are arranged slightly 40 beyond the circumference of the disk and centrally of the recesses. Mounted on the base plate 1 and arranged to be engaged by the pins 104 is a Geneva gear 105, of ordinary construction. Rigidly secured to the 45 Geneva gear is a spur gear 106 meshing with a gear 107 which in turn meshes with a second gear 108, which meshes with a gear 109 mounted on one end of a shaft 110 mounted in the frame member 57 and having secured 50 to its outer end a gear 111 which meshes with a driving gear 112 rigidly secured to the units counter wheel. The operation of the Geneva mechanism is well understood and it will be apparent that with the parts 55 in their normal positions, as they are shown

in Fig. 2, one of the pins 104 will be in a position to engage a tooth of the Geneva gear 105 upon the first part of the movement of the disk 102, thereby rotating the Geneva gear a distance of one tooth and causing the 70 concave face of the tooth following the one engaged by the pin to be brought into engagement with the edge of the circular disk, thus checking the movement of the Geneva gear and locking the same against further 75 movement without interfering with the continued rotation of the disk. The ratio of the gearing interposed between the Geneva gear and the units counter wheel 101 is such as to cause that counter wheel to be advanced 80 one unit each time the Geneva gear is advanced the space of one tooth. Suitable transfer mechanism, which may or may not be similar to that used for the time recording device, is utilized to transfer the count 85 from the units counter wheel to the tens counter wheel, and from the tens counter wheel to the hundreds counter wheel of the consecutive numbering device. In this manner the consecutive number will be changed 90 at the beginning of each operation of the bolt actuating device, and in addition to providing a consecutive number for the record this device also serves to indicate the direction in which the bolt was moved, this being 95 indicated by the character of the number, an odd number indicating the movement of the bolt in one direction and an even number indicating the movement of the bolt in an opposite direction. In the present arrangement an even number indicates that the bolt was moved into its inoperative position, that is, that the door was opened.

The key identifying device is arranged in printing alinement with the counter wheels, 105 as above described, but is not, in the present embodiment of the invention, in the form of what is known as a counter wheel. As here shown the key identifying device comprises a disk-like type carrying member 113 having mounted on the face thereof in circular arrangement a series of type, each of which is adapted to print a mark corresponding with a mark on one of the keys. Preferably the identifying marks are in the form 110 of letters, as here shown, and each key issued is marked with a different letter, the letters corresponding to the type on the type carrying member 113. This type carrying member is provided with a trunnion 114 115 which is journaled in a bearing 115 carried by the upper part of the frame 57 and so arranged that the type carrying member will be supported with one side of the upper surface thereof in a position to maintain the 120 type thereon in printing alinement with the type on the counter wheels. Rigidly secured to the type carrying member 113 is a shaft 116 which is journaled at its lower end in a bearing 117, also carried by the frame 130

member 57, and is provided between its ends with a pinion 118 rigidly secured thereto and meshing with a rack 119 mounted for reciprocatory movement transversely of the 5 shaft 116. Transverse movement is imparted to the rack 119 by means of the key which is used to release the bolt actuating devices and the amount of this movement, and hence the particular identifying mark, which is 10 moved into printing position, is controlled by the length of the key, the several keys issued for any one lock being of different lengths. The rack may be mounted in any suitable manner. In the present instance 15 it is provided at its inner end with a guide-block, which is here shown in the form of a piston head 120, slidably mounted in the hollow shaft or cylinder 59. The opposite end of the rack is supported by a similar 20 guide-block 121, slidably mounted in a cylinder or guide-way 122 mounted in the base plate. A spring 123 confined between the inner guide block 120 and the screw head 80 at the end of the shaft 59 tends to move 25 the rack outwardly and thus retain the type carrying member 113 in its normal position. As here shown the rack 119 is connected with each guide-block at one side of its center and a connecting rod 124 is secured to said 30 guide-blocks on those sides of their center opposite the rack to maintain them in proper alignment. Connected with the rack is a rod 125 having a flat disk-like head 126 arranged adjacent to the inner end of 35 the key barrel 50 and adapted to be engaged by the end of a key inserted in said barrel, and thus impart movement to the rack. Preferably this rod is screw-threaded into the guide-block 121 so as to adjust the 40 operative length of the actuating device for the type carrier and thereby regulate the movement thereof so as to cause the type thereon to be brought into proper printing alignment with the type on the counter 45 wheels. It will be obvious that the adjustment of this rod relatively to the guide-block 121 will move the head 126 toward or from the key barrel, thus causing a greater or lesser movement to be imparted thereto 50 by the key. A locking nut 127 is mounted on the screw-threaded plunger to hold the same against accidental displacement with reference to the guide-block. The spring 123 which holds the rack, and consequently 55 the type carrying member 113, in their normal positions also serves to eject the key, or to partially eject the same, from the key barrel. It will be obvious that when the key is in the barrel it will be subjected to a 60 constant pressure by the spring 123. As soon as the movement of the bolt actuating devices has been completed and the key barrel has been released so that it automatically returns to its normal position, the pressure 65 of the spring will force the key outwardly

thus either partially or completely ejecting the same.

The fixed form for printing the store or machine number on the record may be mounted in any suitable manner. In the 70 present instance the upper end of the frame member 58 is provided with a socket 128 on which the printing characters comprising the form are mounted, this socket being so arranged as to support the type or printing 75 characters in printing alignment with the type on the counter wheel.

Various mechanisms may be provided for taking an impression from the marking or printing devices hereinbefore described, but 80 I prefer to utilize for this purpose a reciprocatory platen which is here shown as an elongated bar 129 having a shank or bearing portion 130 slidably mounted in a vertical bearing 131 formed in a bearing bracket 132 85 rigidly secured to the base plate 1. This platen is provided with a narrow elongated contact surface adapted to engage only the line of type which is in printing position and of such length that it will only engage the 90 type on that side of the type carrying member 113 adjacent to the consecutive numbering device, thus printing from a single character on that type carrying member. This platen is actuated by the bolt actuating devices in such a manner that a record will be made for every movement of the bolt either 95 into or out of its operative position, and the arrangement is preferably such that the record will be made before the bolt is moved, 100 thus insuring that a record will be preserved before the bolt can be moved into a position to release the door no matter how slight a movement may be necessary to accomplish that result. In the construction here illustrated the platen is operated directly from the bolt actuating shaft 7 and to accomplish this I have connected the upper end of the shank 130 of the platen with a yoke 133 through which the shaft 7 extends, the yoke 110 being slotted to permit it to have movement transversely of the shaft. A spring 134 connected with the upper end of the yoke tends to hold the same and the platen normally in their elevated positions. Rigidly secured to 115 the shaft between the side members of the yoke is a cam 135 having two projections, or operative portions, arranged on diametrically opposite sides thereof so that on each half rotation of the shaft one of the operative 120 portions of the cam will engage a part of the yoke and move the same downward against the tension of the spring 134, thereby moving the platen into engagement with the type. Preferably the yoke is provided 125 with a roller 136 against which the cam engages, thus reducing the friction and facilitating the operation of the shaft. To cushion the impact of the platen against the 130 type and to permit the platen to accommo-

date itself to any slight variations in the movement thereof I prefer to connect the platen with the yoke 133 by means of a pin 137 slidably mounted in the end of the shank 130 and having a head 138 arranged within the shank 130, which is made hollow to receive the same. A spring 139 confined between the end of the hollow shank and the head holds the pin 137 normally in its uppermost position to permit the platen to move upward relatively thereto, thereby providing a cushioned contact with the type.

The record is printed on a suitable record sheet, which is preferably in the form of a web or strip of paper which is carried in the form of a roll 140 on one side of the platen and passes about guide pins 141, adjacent to the printing surface, to a second roll 142 rotatably mounted on the opposite side of the platen. The record strip is fed forward automatically upon each operation of the mechanism to provide a suitable space between the successive records. In the present instance this feeding of the paper is accomplished through the Geneva mechanism which actuates the consecutive counter, the Geneva gear itself being rigidly secured to the shaft of the rewinding roller 142 upon which the record strip is wound as it comes from the platen. The movement imparted to the Geneva gear upon each operation of the shaft is sufficient to advance the paper the desired distance. The type may be inked in any suitable manner but I prefer to utilize an inking ribbon 143 which is carried by spools 144 and 145 arranged on opposite sides of the platen and is preferably adjusted by hand.

It will be noted, by an inspection of Fig. 2, that the several mechanisms operated by the actuating shaft are so connected with that shaft that they will be operated in succession, and not simultaneously, thus distributing the load and facilitating the movement of the shaft. As has been stated the Geneva mechanism is so arranged that the paper feeding device and the consecutive number mechanism will be actuated by the first portion of the movement of the shaft. Immediately upon the completion of the operation of these devices the cam 135 engages the roller 136 and actuates the platen, and following the operation of the platen the bolt actuating cam 11 operatively engages one of the projections 12 and moves the bolt.

It is also desirable in some instances to provide means for indicating whether or not the casing 3 has been removed and if so, how often. For this purpose I have mounted on the front wall of the casing an ordinary counter 146 which is readable through an opening in the casing, as shown in Fig. 9, and have provided means whereby this counter will be actuated each time the

casing is removed, or in event the casing should be hinged to the base plate the counter would be operated each time the casing was moved to its open position. To accomplish this a fixed finger 147 is mounted 70 within the casing, on a fixed part of the mechanism, and is arranged to engage an arm 148, which actuates the counting mechanism, and move the same outward, as shown in Fig. 1, when the casing is placed 75 in position on the base. As is usual in counters of this kind, the actuating arm is spring operated in one direction. Consequently when the casing is removed and the actuating arm is moved away from the fixed 80 finger 147 it will be moved to its normal position and one unit will be registered upon the counter. It is immaterial whether the registering mechanism is actuated upon the forward or return stroke of the actuating 85 arm because the mechanism is such that the placing of the casing in position on the base and its removal therefrom will necessarily cause the arm to make one complete operation, that is to be moved first in one direction 90 and then the other so that each time the casing is removed and again placed in position one unit will be added to the count.

The operation of the mechanism will be readily understood from the foregoing description and it will be apparent that I have produced a recording lock in which the actuating device for the bolt and recording mechanism is actuated by an operating member which can be turned in one direction 100 only, and that this movement is utilized to successively operate the several parts of the mechanism; that said actuating device is normally locked against movement and can be released only by the use of a key, which 105 when it has been turned to release the actuating devices will be locked against removal and can only be released by the completion of the operation of said actuating device, thus causing the movement of the bolt to be 110 completed and a record to be made. It will also be noted that I have provided a time recording mechanism which is actuated from a source of stored energy independent of, but controlled by, the clock 115 mechanism so that ample power will be provided for positively advancing the recording devices and but very little load will be imposed upon the clock, thus avoiding all interference with the accuracy of its operation. It will also be apparent that I have so constructed and arranged the several parts of the mechanism as to provide a mechanism which as a whole is very simple in its construction and certain in its operation, 120 and which can be produced and maintained at a relatively small cost.

The records produced by the recording mechanism are printed in plain letters and figures, reading from left to right, the only 130

arbitrary symbol used being the A. M. and P. M. indication. Instead of printing upon the record the letter "A" or the letter "P", or both, to indicate the portion of the day in which the record was made, I have provided for placing a bar beneath the hour during the one half of the day, say the post-meridian period, and the presence of this bar will indicate that the hour is P. M., while its absence will indicate that the hour is A. M. The hour wheel, as has been stated, is provided with twenty-four numerals consisting of two sets of the numerals 1 to 12 inclusive, and the bar is placed beneath each numeral of one set of numerals. In Fig. 11 I have shown a portion of a record strip containing five records covering a period of twenty-four hours. The letter at the left hand margin of the strip indicates the key used to release the mechanism when the record is made, and hence indicates the person, the holder of that key, who manipulated the lock. Following the key identifying letter is the consecutive number, the even numbers indicating that the door was locked and the odd numbers indicating that the door was unlocked. Following the consecutive number are the month and day numbers, and next to these are the hour and minute numbers, while at the right hand margin of the strip is printed the store or machine number. From this explanation it will be noted that the record as shown in Fig. 11 will be translated as follows. Store No. 1717 was opened by the holder of key at 7.30 A. M. on April 26th and was closed at 5.30 P. M. on the same day by the holder of key B. At 11.50 P. M. that same night, April 26th, the holder of key K entered the store and remained for twenty-five minutes, the store having been again locked by him at 12.15 A. M. on April 27th. At 7.25 A. M. on April 27th the store was opened by the holder of key D. The first two and the last records were made in the regular course of business, but it remains for the holder of key K to explain why he entered the store between the closing and opening hours.

While I have shown and described one embodiment of my invention it will be understood that this is chosen for the purpose of illustration only and I do not wish to be limited to the details of construction as various modifications will occur to a person skilled in the art.

Having now fully described my invention, what I claim as new and desire to secure by Letters Patent, is:

1. In a lock, a bolt, a recording device comprising a platen, an actuating device comprising a shaft capable of rotation in one direction only, a cam mounted on said shaft for rotation therewith, said bolt having parts arranged on opposite sides of said cam to be engaged thereby, said cam being

of such a shape that a half rotation of said shaft will cause said bolt to be projected and the succeeding half rotation will cause said bolt to be retracted, and an operative connection between said shaft and said platen to cause a complete operation of said platen upon each half rotation of said bolt. 70

2. In a lock, a bolt, a recording device comprising a platen, an actuating shaft, a cam mounted on said actuating shaft for rotation therewith, said bolt having parts co-operating with said cam to cause said bolt to be projected when said cam moves through a half rotation in one direction and to be retracted when said cam moves through another half rotation in the same direction, a second cam mounted on said shaft for rotation therewith, and a part operatively connected with said platen and arranged to be engaged by said second cam to cause operative movement to be imparted to said cam, said second cam being of such a shape that said platen will be operated upon each half rotation of said shaft. 80 85

3. In a device of the character described, 90 a group of alined counterwheels, a spring arranged in axial alinement with said counterwheels and operatively connected with one of them, clock mechanism, and an escapement actuated by said clock mechanism 95 to control the movement of said counterwheel by said spring.

4. In a device of the character described, 100 a group of alined counterwheels, a gear secured to one of said counterwheels, an escapement wheel secured to said counterwheel, a spring arranged in axial alinement with said counterwheel, gearing connecting said spring with the first mentioned gear, a clock mechanism, and an escapement pawl 105 actuated by said clock mechanism and co-operating with said escapement wheel to control the movement of said counterwheel by said spring.

5. In a lock, a bolt, a key controlled actuating device for said bolt, a recording device comprising a series of alined counterwheels, clock controlled mechanism for actuating a part of said wheels to record the time, an operative connection between said 110 bolt actuating device and another part of said counterwheels to cause the latter to record the operations of said bolt, a platen to cause a record to be taken from said counterwheels, and means actuated by said 115 actuating device to operate said platen. 120

6. In a lock, a bolt, a key controlled actuating mechanism for said bolt comprising a shaft, a recording device comprising a plurality of alined counterwheels, a spring operatively connected with a part of said counterwheels to actuate the same, a clock actuated device to control the operation of said part of said counterwheels, a geared connection between another part of said 125 130

counter wheels and said shaft to cause the last-mentioned part of said counter wheels to make a record of the operations of said shaft, a reciprocatory platen to take a record from said counter wheels, a spring tending to move said platen in one direction, and a cam mounted on said shaft to move said platen in the opposite direction.

7. In a lock, a bolt, an actuating shaft rotatable in one direction only, means to lock said shaft normally against rotation, a key controlled device to move said locking means into an inoperative position, means to cause said locking means to be moved into locking position at the end of each half rotation of said shaft, a cam carried by said shaft and arranged to move said bolt in one direction when a half rotation is imparted to said shaft, and to move said bolt in the opposite direction upon the next half rotation of said shaft, a recording device comprising printing counters, a platen to take a record from said counters, and means connected with said shaft to cause said platen to be operated once for each half rotation of said shaft.

8. In a lock, a bolt, an actuating shaft rotatable in one direction only, means to lock said shaft normally against rotation, a key controlled device to move said locking means into an inoperative position, means to cause said locking means to be moved into locking position at the end of each half rotation of said shaft, a cam carried by said shaft and arranged to move said bolt in one direction when a half rotation is imparted to said shaft, and to move said bolt in the opposite direction upon the next half rotation of said shaft, a recording device comprising a series of alined type wheels, an actuating device for imparting movement to a part of said type wheels, clock actuated means to control the operation of said part of said type wheels, a platen to take a record from said type wheels, and means actuated by said shaft to impart operative movement to said platen upon each half rotation of said shaft.

9. In a lock, a bolt, an actuating shaft rotatable in one direction only, means to lock said shaft normally against rotation, a key controlled device to move said locking means into an inoperative position, means to cause said locking means to be moved into locking position at the end of each half rotation of said shaft, a cam carried by said shaft and arranged to move said bolt in one direction when a half rotation is imparted to said shaft, and to move said bolt in the opposite direction upon the next half rotation of said shaft, a recording device comprising a series of alined type wheels, an actuating device for imparting movement to a part of said type wheels, clock actuated means to control the operation of said part

of said type wheels, a type carrier mounted in printing alinement with said type wheels, key actuated means to adjust said type carrier to print a key identifying mark, a platen to take a record from said type wheel and said type carrier, and means actuated by said shaft to impart operative movement to said platen upon each half rotation of said shaft.

10. In a lock, a bolt, an actuating shaft rotatable in one direction only, means to lock said shaft normally against rotation, a key controlled device to move said locking means into an inoperative position, means to cause said locking means to be moved into locking position at the end of each half rotation of said shaft, a cam carried by said shaft and arranged to move said bolt in one direction when a half rotation is imparted to said shaft, and to move said bolt in the opposite direction upon the next half rotation of said shaft, a recording device comprising a series of alined type wheels, an actuating device for imparting movement to a part of said type wheels, clock actuated means to control the operation of said part of said type wheels, an operative connection between another part of said type wheels and said shaft to cause each half rotation of said shaft to be recorded, a type carrier mounted in printing alinement with said type wheels, key actuated means to adjust said type carrier, a platen to take a record from the several type wheels and from said type carrier, and means actuated by said shaft to cause a complete operation of said platen for each half rotation of said shaft.

11. In a lock, a bolt, a bolt actuating shaft, a recording device comprising a series of type wheels, clock controlled mechanism for actuating a part of said type wheels, a geared connection between another part of said type wheels and said shaft, a platen to take a record from said type wheels, and means actuated by said shaft to actuate said platen, the instrumentalities actuated by said shaft being so arranged that the first movement of said shaft will cause said gearing to actuate said type wheels, that a further movement of said shaft will cause said platen to be actuated, and a further movement will cause said bolt to be actuated.

12. In a lock, a bolt, a bolt actuating shaft, a recording device comprising a series of printing counters, a circular disk carried by said shaft having a notch in the periphery thereof, a pin mounted adjacent to said notch, a Geneva gear arranged to be actuated by said pin, and to operatively engage the periphery of said disk, and geared connections between said Geneva gear and said type wheels.

13. In a lock, a bolt, a bolt actuating shaft, a recording device, a platen to take a

record from said recording device, an operative connection between said platen and said shaft, means for feeding paper to said recording device comprising a rewinding roll, a Geneva gear connected with said rewinding roll, an actuating disk carried by said shaft and coöperating with said Geneva gear, and a geared connection between said Geneva gear and said recording device to cause a record to be made of the operation of said shaft.

14. In a lock, a bolt, a key controlled actuating device for said bolt, a recording device comprising a series of counter wheels, a rotatable type carrier mounted in printing alinement with said type wheels, a pinion connected with said type carrier, a rack meshing with said pinion, key actuated means for moving said rack, and means for taking a record from said recording device.

15. In a lock, a bolt, a key controlled actuating device therefor, a recording device comprising a plurality of type wheels, a disk-like type carrier mounted adjacent to said type wheels on an axis extending transversely to the axis thereof, a pinion connected with said disk-like type carrier, a rack meshing with said pinion, a part connected with said rack and arranged to be engaged by the key to control said actuating device, and means for taking a record from said recording device.

16. In a lock, a bolt, a key controlled actuating device for said bolt, a recording device comprising a hollow shaft, type wheels rotatable about said shaft, a type carrier rotatable about an axis intersecting the axis of said hollow shaft, a pinion connected with said type carrier, a rack meshing with said pinion adapted to travel in said hollow shaft, and a part connected with said rack and arranged to be engaged by the key which controls said actuating device.

17. In a lock, a bolt, a key controlled actuating device for said bolt, a recording device comprising a hollow shaft, type wheels rotatable about said shaft, a type carrier rotatable about an axis intersecting the axis of said hollow shaft, a pinion connected with said type carrier, a rack meshing with said pinion, a guide-block mounted in said hollow shaft, a spring acting on said guide-block to move said rack in one direction, a part connected with said rack and arranged to be engaged by the key which controls said

actuating device, and means to take a record from said recording device.

18. In a lock, a bolt, a key controlled actuating device for said bolt, a recording device comprising a plurality of type wheels, a type carrier arranged adjacent to said type wheels and rotatable about an axis intersecting the axis of said type wheels, a pinion connected with said type carrier, a guide-way arranged axially of said type wheels on one side of said pinion, a second guide-way arranged in alinement with said first guide-way on the opposite side of said pinion, guide-blocks mounted in said guide-ways, a rack connected with said guide-blocks and meshing with said pinion, a part connected with said rack and arranged to be engaged by the key which controls said actuating device, and means to take a record from said recording device.

19. In a lock, a bolt, a key controlled actuating device for said bolt, a recording device comprising a series of type wheels, a type carrier arranged in printing alinement with said type wheels and rotatable about an axis extending transversely of said type wheels, a pinion extending transversely of said type carrier, a rack meshing with said pinion, a part connected with said rack and arranged to be engaged by the key which controls said actuating device, means for adjusting said key engaging part relatively to said rack, and means to take a record from said recording device.

20. A key actuated identifying device comprising a rotatable type carrier, a pinion connected therewith, a rack meshing with said pinion, a part connected with said rack and arranged to be engaged by the key, and means for adjusting said part relatively to said rack.

21. A key controlled identifying device comprising a disk-like type carrier having type on the face thereof, and rotatable about an axis extending transversely to the plane of said type, a pinion connected with said type carrier, a rack meshing with said pinion, a guide for said rack, a rod adjustably secured to said rack, and a head carried by said rod and arranged to be engaged by the key.

In testimony whereof I affix my signature hereto.

THOMAS A. KEEFER.
